TELEPHONE RINGING APPARATUS WITH
VIBRATORY REED OF MAGNETIC MATE-
RIAL

James M. Blackhall and Franklin J. Hickman,
Galion, Ohio, assignors to The North Electric
Manufacturing Company, Galion, Ohio, a cor-
poration of Ohio

Application March 5, 1947, Serial No. 732,458

10 Claims. (Cl. 179—87)

1

This invention relates, generally, to telephone ringing apparatus, and it has particular relation to vibrator type of ringing devices by means of which direct current is caused to flow intermittently through the primary winding of a transformer for causing alternating current to flow in the secondary winding thereof at a frequency which is determined by the frequency of vibration of the ringing device.

Among the objects of this invention are: To increase the efficiency of the magnetic circuit of ringing devices of the vibrator type; to employ magnetic material for the vibrator reed thereby requiring only one driving coil and avoiding the use of an independent armature; to anchor one end of the reed to one of the pole pieces making up the magnetic circuit so that in vibrating it flexes relative thereto; to employ an air gap in the magnetic circuit bridged by the reed that is relatively short as compared to the length of the magnetic circuit; to adjust the length of the magnetic circuit; to provide for varying the frequency of vibration of the reed; and to adjust the reed assembly so that it will vibrate at the desired frequency.

Other objects of this invention will, in part, be obvious and in part appear hereinafter.

Accordingly, this invention is disclosed in the embodiment thereof shown in the accompanying drawings, and it comprises the features of construction, combination of elements and arrangement of parts which will be exemplified in the construction hereinafter set forth and the scope of the application of which will be indicated in the appended claims.

For a more complete understanding of the nature and scope of this invention, reference may be had to the following detailed description, taken together with the accompanying drawings, in which:

Figure 1 is a view, in side elevation, of the ringing device shown in Figure 2, one of the contact brackets being broken away in order to illustrate more clearly certain details of construction;

Figure 2 is a view, in front elevation, of the ringing device;

Figure 3 is a top plan view of the ringing device shown in Figure 2;

Figure 4 is a detail sectional view, at an enlarged scale, taken along the line 4—4 of Figure 2; and

Figure 5 illustrates, diagrammatically, the electric circuit connections that can be employed

2

in the use of the ringing device shown in Figures 1 through 4 and described in detail hereinafter.

Referring now particularly to Figures 1, 2, 3 and 4 of the drawings, it will be observed that the reference character 10 designates a base plate which is formed of non-magnetic material, such as brass. The base plate 10 may be formed from plate stock having a thickness of $\frac{1}{2}$ inch, a width of $1\frac{1}{2}$ inches, and a length of $4\frac{1}{8}$ inches.

10 The magnetic circuit for the ringing device is located at the upper right-hand corner of the base plate 10 as viewed in Figure 2. The magnetic circuit includes an upper pole piece 11 that is generally L-shaped and preferably is formed of annealed cold rolled steel. The pole piece 11 may be secured flat against the surface of the base plate 10 by countersunk screws 12 and 13 that extend from the opposite side into the pole piece 11. The stock making up the pole piece 11 preferably has a thickness of $\frac{1}{8}$ inch. The short arm 14 of the pole piece 11 may be $1\frac{1}{4}$ inches long, while the longer arm 15 may be $2\frac{1}{2}$ inches long. The arms 14 and 15 each may have a width of $\frac{3}{8}$ inch. The lower portion of the outer surface of the longer arm 15 is recessed, as indicated at 16, about .025 inch from the lower end to a point midway thereof for a purpose which will be apparent presently. The lower end 17 of the longer arm 15 may have a width of $\frac{1}{2}$ inch and then, as indicated at 18, the lower surface may be cut away at an angle of 45 degrees.

35 The magnetic circuit also includes a lower pole piece that is indicated, generally, at 19 which has an angular configuration and is formed of annealed cold rolled magnetic iron. The lower pole piece 19 has one side 20 which is held flat against the upper surface of the base plate 10 by a screw 21 that extends through an elongated opening 22 in the side 20. The purpose of the elongated opening 22 is to permit adjustment of the lower pole piece 19 in a direction at right angles to the longer arm 15 of the L-shaped upper pole piece 11. The lower pole piece 19 is preferably formed of stock having a thickness of $\frac{1}{8}$ inch and the side 20 may have a width of $\frac{3}{8}$ inch and a length of $1\frac{1}{8}$ inches. The other side 23 of the lower pole piece 19 extends at right angles to the side 20 and has a width of $\frac{1}{8}$ inch which is the same as the thickness of the upper pole piece 11. It has an overall length of $1\frac{1}{8}$ inches. As shown more clearly in Figure 4, the side 23 of the lower pole piece 19 has an elongated slot 24 through which a screw 25 projects into 50 a core 26 of magnetic material. The slotted open-

ing 24 is provided to permit adjustment of the lower pole piece 19 in the manner described hereinbefore.

As indicated the core 26 is formed of magnetic material. It may be formed from cold drawn magnetic iron rod and it may have a diameter of $\frac{3}{8}$ inch. It has a length of $1\frac{1}{8}$ inches and extends between the opposed faces of the side 23 of the lower pole piece 19 and of the shorter arm 14 of the upper pole piece 11. A screw 21 extends through the arm 14 into the upper end of the core 26 for securely holding the same in place. An energizing winding or coil 28 is located on the core 26 and, as will be described hereinafter, it serves to energize the magnetic circuit described for operating the ringing device.

As shown more clearly in Figures 2 and 4 of the drawings, the side 23 of the lower pole piece 19 has an extension 29, the ends 30 of which are cut off at approximately 45 degrees for concentrating the flux in the magnetic circuit flowing to or from the short width tip 17 of the arm 15 that forms a part of the upper pole piece 11. This magnetic flux, in part, flows across an air gap 31 between the extension 29 and the tip 17, and it has a fixed length which is relatively short as compared to the length of the magnetic circuit or more particularly to the length of the longer arm 15 of the upper pole piece 11. For example, the air gap 31 may have a length of $\frac{3}{16}$ inch. Satisfactory results are obtained using this length of air gap when the other proportions of the magnetic circuit are as specified.

Now it will be observed that the upper pole piece 11, the lower pole piece 19 and the core 26 form a generally rectangular magnetic circuit having an air gap 31 in one side thereof the length of which is relatively short as compared to the entire length of the magnetic circuit. Because of the relatively short length of the air gap 31 as compared to the length of the magnetic circuit, its efficiency is increased, leakage flux is reduced, and less power is required for energizing the coil 28 to obtain satisfactory operation of the ringing device.

The moving part of the ringing device comprises a reed 32 that may be formed of annealed spring steel, tempered to the desired hardness, and it may be secured by screws 33 to the upper end of the longer arm 15 of the upper pole piece 11, as illustrated more clearly in Figures 1 and 2 of the drawings. The reed 32 may have a length of six inches, a width of $\frac{5}{16}$ inch and may have a thickness of either .049 or .083 inch, depending upon the frequency of vibration as will be described in more detail hereinafter. Since the reed 32 is fixed to the upper pole piece 11, it flexes relative thereto, and it is to permit this action that the longer arm 15 is recessed as indicated at 16. The reed 32 extends along the arm 15 over the recessed surface 16 and in overlapping relation past the air gap 31. Since the reed 32 is formed of magnetic material, it is unnecessary to provide a separate armature for cooperating with the upper and lower pole pieces 11 and 19 to attract the same thereto on energization of the coil 28. The reed 32 cooperates with the upper and lower pole pieces 11 and 19 to form variable length upper and lower air gaps 31a and 31b disposed above and below the fixed length air gap 31 and in shunting relation thereto. The aggregate length of these upper and lower variable length air gaps 31a and 31b is less than the length of the fixed air gap 31.

On opposite sides of the reed 32 power contact springs 34 are located and spaced therefrom by metal spacers 35. The contact springs 34 are reinforced by power contact spring supports 36 which, as indicated in Figure 1, have their lower portions recessed as indicated at 37 so as not to interfere with the movement of contacts 38 that are carried by the power contact springs 34 near their lower ends. The contacts 38 may have a diameter of $\frac{1}{16}$ inch and be formed of tungsten with a nickel backing. They may be secured, as by welding, to the power contact springs 34. The contacts 38 are arranged to engage contacts 39, of tungsten or the like, that are carried at the inner ends of contact screws 40 which are threaded in power contact screw brackets 41 that are suitably insulated from opposite sides of the base plate 10 and secured thereto by screws 44, as illustrated. Connection to the screws 40 may be had by terminal strips 45 to which conductors can be secured as by soldering, as will be readily understood.

The reed 32 also carries a motor contact spring 46 that is spaced from the left-hand power contact spring support 36 by insulating spacers 47. The motor contact spring 46 is reinforced by a motor contact spring support 48 and it carries a contact 49, similar to the contacts 38, for engaging the contact 50, similar to the contact 39, that is carried at the inner end of a motor contact screw 51 which is threaded in a bracket 52 that is suitably insulated from the base plate 10 and secured thereto by screws 55. Connection to the contact screw 51 may be had by a terminal strip 56. The motor contact spring support 48 has an extension 57' to which connection can be made to one terminal of the coil 28. This extension 57' carries the point of connection back to the point of least vibration, thus reducing to a minimum the vibration on the connecting wire.

It will be observed that the power contact springs 34 and the associated power contact spring supports 36 together with the motor contact spring 46 and its associated motor contact spring support 48 are mounted on the reed 32 for movement therewith just below the air gap 31. They are securely clamped in place on opposite sides of the reed 32 by screws 57 which extend therethrough, as indicated in Figure 4, and are threaded into a plate 58. An insulating sleeve 59 extends over the shank of each of the screws 57 for the purpose of insulating the motor contact spring 46 and the motor contact spring support 48 therefrom. The power contact springs 34 are in circuit with the reed 32 so that it is unnecessary to insulate them therefrom. Connection thereto can be made merely by making a connection to the base plate 10.

As indicated hereinbefore, the frequency of vibration of the reed 32 is determined, in part, by its thickness. Another factor that is involved in determining the frequency of its vibration is the mass of the weight that is located at its lower end. For this purpose, discs 62 may be secured eccentrically as by a screw 63 to the lower end of the reed 32. As shown, the discs 62 are round and may be formed of metal, such as brass. Each disc may be provided with a punched out projection 64 for cooperating with a similarly shaped recess 65 in an adjacent disc 62 for keeping them in proper register. As will appear, hereinafter, more than one disc 62 may be located on each side of the reed 32 to provide different frequencies of vibration. It is when they are thus juxtaposed

that the projections 64 and recesses 65 function to maintain the required alignment.

Since the discs 62 are positioned eccentrically on the lower end of the reed 32, it is possible to shift them from one position to another, as illustrated by the broken outline thereof in Figure 1, so as to provide a fine adjustment of the frequency of vibration of the reed 32. For purposes of illustration, it is pointed out that each of the discs 62 may have a diameter of $\frac{1}{8}$ inch and a thickness of $\frac{1}{16}$ inch.

The ringing device illustrated in Figures 1, 2, 3 and 4 and described hereinbefore can be used, with suitable modifications, for generating ringing frequencies ranging from $16\frac{2}{3}$ cycles per second to $66\frac{2}{3}$ cycles per second. For each frequency a separate ringing device is provided with an appropriate thickness of the reed 32 and number of discs 62 for the particular frequency. For frequencies ranging from $16\frac{2}{3}$ cycles to $33\frac{1}{3}$ cycles the reed 32 may have a thickness of .049 inch. For the higher frequencies ranging from 42 cycles to $66\frac{2}{3}$ cycles, it may have a thickness of .083 inch. The number of discs 62 for each frequency is set forth in the following table:

Cycles per Second	Number of Discs
$16\frac{2}{3}$	22
20	16
25	8
30	5
$33\frac{1}{3}$	4
42	10
50	6
54	8
$66\frac{2}{3}$	2

The ringing device shown in the drawings and described hereinbefore is preferably mounted in an upright position on a suitable frame or panel. For this purpose mounting openings 66 may be provided at opposite corners of the base plate 10 as illustrated.

In Figure 5 of the drawings, the ringing device, as previously described, is illustrated generally at 70. In this figure are illustrated the circuit connections that can be employed for using this device. It will be noted that a battery 71 is employed and this may be the common battery of a telephone system which may have a normal voltage of 48 volts.

When motor contacts 48 and 50 are engaged, the coil 28 is connected across the 48 volt battery 71 and the reed 32 is attracted to separate these contacts. The energizing circuit for the coil 28 is then broken and the reed 32 swings or flexes in the opposite direction to again cause these contacts to engage. As described hereinbefore, the frequency of movement of the reed 32 is determined by its thickness and the number of discs 62 located on the lower end thereof.

The movement of the reed 32 concurrently causes the power contacts 39 on opposite sides thereof to be engaged and, since the reed 32 is connected to the midpoint of the 48 volt battery 71, a voltage of 24 volts is applied across primary windings 72 and 73 of a transformer that is indicated, generally, at 74. This voltage is applied alternately to the primary windings 72 and 73 so that current flows therein during these periods in the directions indicated by the arrows 76 and 77. As a result an alternating current is induced in a secondary winding 78, which as shown may be connected to the output or ringing circuit represented by conductors 80 of the telephone ex-

change. These conductors 80 can be connected in known manner to a subscriber's circuit for ringing the bells of one or more telephone sets connected thereto. Different frequencies are employed for ringing different parties on the same line and it is for this purpose that the ringing device is constructed so that essentially the same parts can be employed for different devices to generate different ringing frequencies.

In order to prevent the ringing frequency from being applied to the central or common battery 71 suitable filter means can be provided between the ringing device 70 and the battery 71. For example, inductors 83 may be provided in series circuit relation with the conductors to the battery 71 and capacitors 84 may be connected thereacross as illustrated. An inductor 85 and a capacitor 86 may be connected across the conductors 80 to reduce sparking of the power contacts 38-39.

In order to provide a clear and complete disclosure of the invention, various dimensions have been specified and materials mentioned. It will be understood that some variation in these specifications can be made without departing from the spirit and scope of this invention. Accordingly, it is intended that all matter shown in the accompanying drawings and described hereinbefore shall be interpreted as illustrative and not in a limiting sense.

What is claimed as new is:

1. In telephone ringing apparatus, in combination, a base plate of non-magnetic material, an upper L-shaped pole piece of magnetic material secured flat on said base plate having the lower surface of the longer arm recessed from the outer end to about midway of its length, a lower angular pole piece of magnetic material having one side secured to said base plate and the other side disposed parallel to the shorter arm of said upper pole piece and spaced from said outer end of said longer arm thereof to form a fixed length air gap therebetween, a magnetic core extending between said short arm of said upper pole piece and said other side of said lower pole piece and secured thereto, a coil on said core, a reed in the form of a flat strip of spring magnetic material secured at one end to the upper end of said longer arm of said upper pole piece and extending over said recessed outer surface thereof and said fixed length air gap for a substantial distance beyond the same, said reed coacting with said upper and lower pole pieces to form upper and lower variable length air gaps extending in shunting relation to said fixed length air gap, the aggregate length of said upper and lower variable length air gaps being less than the length of the fixed length air gap, motor contact means operated by said reed for intermittently opening and closing an energizing circuit for said coil to vibrate said reed, and power contact means operated by said reed to close and open a telephone ringing circuit.

2. The invention, as set forth in claim 1, wherein the length of the fixed length air gap is relatively short as compared to the length of the longer arm of the upper pole piece.

3. The invention, as set forth in claim 2, wherein the motor contact means includes a stationary contact carried by the base plate and a cooperating movable contact spring supported by the reed, and the power contact means includes a pair of stationary contacts carried by said base plate on opposite sides of said reed and a pair of cooperating movable contacts spring supported by said reed on opposite sides thereof.

4. The invention, as set forth in claim 3, wherein the spring supports for the movable motor and power contacts are fastened to the reed adjacent the air gaps and they extend away therefrom along said reed.

5. The invention, as set forth in claim 4, wherein weight means for adjusting frequency of vibration is provided at the other end of the reed, which frequency of vibration is determined by the thickness and the mass of said weight means.

6. The invention, as set forth in claim 1, wherein weight means in the form of one or more metallic discs is provided at the other end of the reed and eccentrically mounted thereon and the frequency of vibration thereof is determined by its thickness, the number of said discs and the position thereof relative to said reed.

7. The invention, as set forth in claim 1, wherein in the lower pole piece is adjustable in a direction of right angles to the longer arm of the upper pole piece for varying the length of the lower variable length air gap.

8. In telephone ringing apparatus, the combination of a magnetic core, a coil on said core, a first pole piece extending from one end of said core, a second pole piece extending from the other end of said core, adjacent ends of said pole pieces establishing a fixed length air gap therebetween adapted to be threaded by flux lines, a magnetic reed extending substantially parallel to the path of the flux lines threading said fixed length air gap, said reed being spaced slightly from said ends of both pole pieces to establish a first variable length air gap between said first pole piece and said reed and to establish a second variable length air gap between said second pole piece and said reed, said two variable length air gaps being connected magnetically in series through said reed and creating a second flux path in shunt of the flux path through said fixed length air gap, motor contact means operated by said reed for intermittently opening and closing an energizing circuit for said coil to vibrate said reed, and power contact means operated by said reed to close and open a telephone ringing circuit.

9. In telephone ringing apparatus, the combination of a magnetic core, a single coil on said core, a first pole piece extending from one end of said core, a second pole piece extending from the other end of said core, the adjacent ends of said pole pieces establishing a fixed length air gap therebetween adapted to be threaded by flux lines, a reed in the form of a flat strip of spring magnetic material secured at one end to one of said pole pieces and extending substantially parallel to the path of the flux lines threading said fixed length air gap, the free portion of said reed being spaced slightly from said ends of both pole pieces to establish a first variable length air gap between said first pole piece and said reed and to establish a second variable length air gap between said second pole piece and said reed, said two variable length air gaps being connected mag-

netically in series through said reed and creating a second flux path in shunt of the flux path through said fixed length air gap, the aggregate lengths of said two variable length air gaps being less than the length of said fixed length air gap, means for adjusting the position of one of said pole pieces relatively to the other so as to adjust one of said air gaps, motor contact means operated by said reed for intermittently opening and closing an energizing circuit for said coil to vibrate said reed, and power contact means operated by said reed to close and open a telephone ringing circuit.

10. In telephone ringing apparatus of the class described, the combination of a magnetic core, a single energizing coil on said core, an upper pole piece extending from the upper end of said core, a lower pole piece extending from the lower end of said core, the adjacent ends of said pole pieces establishing a fixed length air gap therebetween adapted to be threaded by flux lines on said core, a reed in the form of a flat strip of spring magnetic material having its upper end secured to said upper pole piece and extending downwardly substantially parallel to the path of the flux lines threading said fixed length air gap, the free portion of said reed being spaced slightly from said ends of both pole pieces to establish an upper variable length air gap between said upper pole piece and said reed and to establish a lower variable length air gap between said lower pole piece and said reed, said two variable length air gaps being connected magnetically in series through said reed and creating a second flux path in shunt of the flux path through said fixed length air gap, adjustable mounting means for said lower pole piece enabling the latter to be shifted to adjust the length of said lower variable length air gap, motor contact means operated by said reed for intermittently opening and closing an energizing circuit for said coil to vibrate said reed, a pair of contact springs mounted on opposite sides of the swinging end of said reed, and cooperating relatively stationary contacts adapted to be engaged by said contact springs for closing and opening a telephone ringing circuit.
